Inventor:

Oskar Finkhaus,
by M. Schonborn,
Attorney.

UNITED STATES PATENT OFFICE.

OSKAR FINKHAUS, OF WURZBURG, GERMANY, ASSIGNOR TO BOHN & HERBER,
MASCHINENFABRIK UND EISENGIESSEREI, OF WURZBURG, BAVARIA, GERMANY,
A KOMMANDITGESELLSCHAFT OF GERMAN LAW.

INKING MECHANISM OF PRINTING PRESSES.

Application filed August 2, 1924. Serial No. 729,812.

To all whom it may concern:

Be it known that I, OSKAR FINKHAUS, a citizen of Deutsches Reich, and residing at 34 Petrinistreet, Wurzburg, Bavaria, Germany, have invented certain new and useful Improvements in the Inking Mechanism of Printing Presses; and I do hereby declare that the following is a full, clear, and exact description of the same.

10 The well known cylinder inking devices of high speed printing presses with a preliminary distributing mechanism separated from the inking-in mechanism by an inserted "doctor" roller have, it is true, in themselves considerable advantages as compared with the arrangement without a doctor roller at that point; these well known constructions have however the drawback that the doctor roller, owing to its small 15 circumference, transfers the ink uniformly smoothed out by the preliminary distributing rollers, in a thick layer to the inking roller mechanism, and that therefore the said thick layer has to be distributed down 20 again by the inking roller mechanism. The inking roller mechanism requires at each printing operation as much ink as is consumed for one printing and the quantity is in a definite proportion to the length of 25 the type form. If the circumference of the doctor roller is considerably smaller than the length of the form, the ink must be distributed on it in a correspondingly thicker 30 layer. In well known constructions, the circumference of the doctor roller is only $\frac{1}{4}$ to $\frac{1}{5}$ of the length of the form. The above 35 mentioned drawback is the reason why inking mechanisms with a reciprocating distributing table are preferred to cylinder inking devices.

This invention has for its object to eliminate the said drawback, and consists in arranging, between the preliminary distributing device and the inking roller mechanism, an ink transfer cylinder of a circumference equal to the greatest length of the

type form, the said cylinder being alternately brought in contact with the preliminary distributing mechanism and with the inking roller mechanism. On an ink 50 transfer cylinder of such circumference the ink is then distributed in a much thinner layer than on a doctor roller of the usual diameter. The ink is therefore distributed more uniformly and to greater advantage. 55

If this layer on the transfer cylinder, taken from the preliminary distributing mechanism, is assumed to be a band of a length equal to that of the type form, the volume of ink in the said band will be equal 60 to the volume of the ink placed on the form at each printing operation, that is to say equal to the quantity of ink which, at each printing operation, must be transferred to the inking roller mechanism. The thickness and length of the said layer of ink correspond exactly to those of that layer of ink which, in the inking device according to the invention, is given off by the ink transfer cylinder to the inking roller mechanism. The layer of ink thus given off by the ink transfer cylinder, passes, without 65 its thickness and length being altered, being merely distributed among the various inking rollers, through the inking roller mechanism, without being substantially modified thereby. When therefore a layer 70 of ink of the kind just described is deposited by the preliminary distributing mechanism on the ink transfer cylinder, which can 75 be easily ensured by means of the preliminary distributing mechanism, there is no doubt but that the layer of ink will reach the form in correct distribution.

When for instance a "tone surface", that 85 is to say a surface with a perfectly uniform ink covering is to be printed, the above mentioned thin layer of ink will be able to pass without any modification to the form. Any greater fineness that can be 90 obtained by the preliminary distributing mechanism is therefore unnecessary in any

2
conditions. The circumference to be given according to this invention, to the ink transfer cylinder, is therefore the greatest that is required for the purpose of ensuring uniform distribution of the ink.

In the drawings in which similar reference characters indicate the same parts in the several figures,

Figure 1 is a diagrammatic and fragmentary longitudinal section of a high speed flat form cylinder press showing the invention, and

Figure 2 is a similar view of a modified form of the invention.

15 The inking mechanism of the first construction Figure 2, is constituted by the ink trough *f* with a doctor roller *h*, the preliminary distributing mechanism with the distributing cylinders *r*, *r'* and the distributing rollers *w*, *w'*. These parts constitute the preliminary distributing mechanism. It is followed by the ink transfer cylinder *z* which is made as a bare iron cylinder without any composition covering; adjoining the said 20 cylinder is the inking roller mechanism with the distributing rollers *c*, *c'* and *c''*, distributing cylinders *b*, *b'* and *b''* and inking rollers *a*, *a'* and *a''*.

The ink transfer cylinder is mounted in an 30 eccentric *e* and by turning the said eccentric by means of a rod *g*, can be brought alternately against the distributing roller *w'* and the distributing roller *c*, that is to say alternately against the preliminary distributing 35 mechanism and the inking roller mechanism. The form of the press is indicated at *s*, and *d* is the impression cylinder.

The second example (Figure 1) differs from the first one only by the ink transfer 40 cylinder *z* being fixed in the frame of the machine, whilst the two distributing rollers *w'*, and *c* are mounted on oscillating bell crank levers *m* or *n* which can turn about the axes of the distributing cylinders *r'* or *b*. 45 The bell crank levers *m* and *n* are connected together by a rod *k* and can be turned by means of a rod *l*. During the turning of the bell crank levers *m* and *n*, the distributing rollers *w'* and *c* are brought alternately in and out of contact with the ink transfer 50 cylinder *z* so that the latter is alternately in contact with the preliminary distributing mechanism and with the inking roller mechanism.

55 The operation of the two inking devices illustrated is as follows:—

First the ink transfer cylinder is brought in contact with the preliminary distributing mechanism. The uniform speed of rotation 60 of the preliminary distributing mechanism is so set that the ink transfer cylinder *z*, as long as it remains in connection with the preliminary distributing mechanism, rotates at the same speed as that of the printing carriage or bed during contact with the ink-

ing roller mechanism. The ink transfer cylinder remains in contact with the preliminary distributing cylinder approximately until it has completed two revolutions. Then it is brought by an opposite movement 70 of the rod *g* or *l* into contact with the inking roller mechanism, so that a fresh layer of ink passes from it to the inking roller mechanism. The ink transfer cylinder continues to rotate in the same 75 direction and with the same speed as before. As soon as it has completed one revolution, it is again brought out of contact with the inking roller mechanism, so that it is in contact neither with the latter nor with the 80 preliminary distributing mechanism. After the preliminary rubbing mechanism has been given time to thoroughly distribute the fresh ink, the movement of the rod *g* or *l* is completed, so that the ink transfer cylinder 85 is then again in contact with the preliminary distributing mechanism.

It is not absolutely essential that both oscillating rollers *c* and *w'* in the construction in Figure 1, should be moved simultaneously and by the same rods; on the contrary, the arrangement could be such that both rollers would be in contact with the ink transfer cylinder *z* at different times.

The construction shown in Figure 1 has 95 the advantage that a movement of the heavy ink transfer cylinder and its support become unnecessary, and in place of it, only the relatively light rollers *w'* and *c* are moved. The construction of the ink transfer cylinder of bare iron, without composition covering, has the advantage that this heavy and large cylinder need not be removed from time to time from the machine for the purpose of renewing the composition covering, and that consequently it can be supported in a very simple manner.

Having now particularly described and ascertained the nature of my said invention and in what manner the same is to be performed I declare that what I claim is:—

1. A cylinder inking mechanism for printing presses comprising an ink trough at one end of said press and an impression cylinder at the other end of the press, a rotary ink transfer cylinder interposed between said ink trough and impression cylinder and rotating in one direction, a preliminary ink distributing mechanism interposed between said ink trough and ink transfer cylinder, a type form inking mechanism interposed between the impression cylinder and the ink transfer cylinder, a type form adapted to be brought in contact with said form inking mechanism and impression cylinder, said ink transfer cylinder having a circumference substantially equal to the greatest length of said type form, and means for alternately bringing the cylindrical surface of said ink transfer cylinder in contact with the preliminary ink

distributing mechanism and the form inking mechanism.

2. A cylinder inking mechanism for printing presses according to claim 1, in which the ink transfer surface of said ink transfer cylinder is made of iron or like material.

3. A cylinder inking mechanism for printing presses according to claim 1, in which the ink transfer cylinder rotates upon a fixed 10 axis, a doctor roller arranged between the

ink transfer cylinder and the preliminary ink distributing mechanism on one side, and a doctor roller arranged between the ink transfer cylinder and the form inking mechanism on the other side of said ink transfer 15 cylinder.

Signed at Wurzburg this 19th day of May, 1924.

OSKAR FINKHAUS.
